UNITED STATES PATENT OFFICE.

CHARLES D. LANNING, OF BOSTON, MASSACHUSETTS, ASSIGNOR TO AMERICAN WARP DRAWING MACHINE COMPANY, A CORPORATION OF MAINE.

WARP-LEASING MACHINE.

1,267,090.

Specification of Letters Patent. Patented May 21, 1918.

Application filed April 27, 1914. Serial No. 834,630.

To all whom it may concern:

Be it known that I, CHARLES D. LANNING, a citizen of the United States, and a resident of Boston, county of Suffolk, State of 5 Massachusetts, (whose post-office address is 95 Milk street, Boston, Massachusetts,) have invented an Improvement in Warp-Leasing Machines, of which the following description, in connection with the accompanying 10 drawings, is a specification, like characters on the drawings representing like parts.

This invention relates particularly to warp-leasing machines intended for mechanically leasing a warp and particularly, 15 though not exclusively, a new warp which it is desired to have leased prior to its insertion in the loom.

The invention may be best understood by reference to the following description when 20 taken in connection with the accompanying illustration of one specific embodiment thereof, while its scope will be more particularly pointed out in the appended claims.

In the drawings:

25 Figure 1 is an elevation partly broken away showing principal working parts of a machine embodying one form of the invention, the view being taken from the front or warp supporting side of the machine.

30 Fig. 2 is an elevation in vertical section showing the principal mechanical parts illustrated in Fig. 1 and looking toward the right as viewed in Fig. 1.

Fig. 3 is a detail on an enlarged scale in 35 partial section showing the construction and operation of the lease cord controlling devices.

Fig. 4 is a similar view looking endwise on one of the lease cord controlling devices.

40 Fig. 5 is a view also on an enlarged scale showing in transverse elevation the needle in its advanced position and its relation to the leasing cords in one position of the latter.

45 Fig. 6 is a view similar to Fig. 5 showing the advanced needle but the reversed or shifted relation of the lease cords.

Fig. 7 is an elevation on an enlarged scale 50 of the warp thread separating and selecting device.

Fig. 8 is a longitudinal sectional elevation of the same; and

Fig. 9 is a transverse section taken on the line 9—9 in Fig. 8.

55 While the various elements of the ma-

chine to be described may be arranged in other relations than those set forth, and while the details thereof may be widely varied from those disclosed in the herein specific and illustrative form of machine, 60 there is here provided a carriage sustaining a reciprocatory warp drawing needle and operating mechanism therefor, which carriage is caused to advance progressively lengthwise the machine to traverse the 65 warp, the latter being maintained with its threads under tension and arranged in substantially parallel alinement. The advancing needle is caused to seize the foremost warp thread and to draw the same between 70 suitably positioned lease members, these being herein in the form of flexible cords held at their opposite ends with the required degree of tautness.

Means are provided to coöperate with the 75 needle to strip the drawn thread therefrom and to thrust aside the leased threads from the line of needle action. At suitable times and herein between each successive thread drawing, the relation of the leased cords is 80 shifted by guiding and holding means which are mounted on the needle carriage and travel therewith so that in the described machine the successive threads are left 85 reversely arranged between the lease members. 85

Referring to the drawings and to the 90 illustrative embodiment of the invention, there is provided a suitably supported bed or frame 1 carrying the end frame members 2, 2, which serve as supports for the warp 90 carriage, lease members, and other parts.

The warp is sustained during the operation of the machine in a warp carriage or holder of any suitable construction, but which here comprises a pair of end frame 95 members 3 (one only of which is shown in Fig. 2). These are suitably connected to constitute a warp carrying frame generally similar to that shown in British patent to Brooks No. 4,661 of 1904, and provided with 100 the upper and lower clamping jaws 4 and 5 respectively. The carriage is supported by oppositely extended hanger rods 6 resting on roller supports 7, being thereby maintained for longitudinal adjustment length- 105 wise the machine. The frame members are also provided with lower supporting rods 8 which the weight of the carriage causes to press against vertically disposed rollers 9 on the stationary frame of the machine. The 110

warp threads 10, when positioned in the machine, have the relation represented in Fig. 2 with their free ends loosely held in the usual clamp bar 11. From the clamp bar 11 the threads pass over the thread separator shaft 12 and thence downward and outwardly to the second clamp bar 13 wherein they are tightly held and thence down to the loom beam, the warp thus having its threads 10 supported in angular formation with the separating shaft 12 at the apex of the angle. The upper clamping jaws 4 are adjustably mounted upon supporting rods 14 so that they may be adjusted to put the necessary tension 15 upon the threads over the separator shaft.

The drawing needle 20 is mounted upon a carriage 21 which latter is adapted to slide lengthwise the machine and transversely the warp upon suitable guide-ways formed on the bed of the machine. During the travel 20 of the carriage the needle is given a reciprocatory movement to and from the threads of the warp. The construction of the needle carriage, the traversing mechanism therefor, 25 and needle operating and thread stripping mechanism is substantially the same as that shown in prior patent to Field *et al.*, No. 871,680, dated November 19, 1907, and need only be briefly referred to. To advance the 30 carriage the latter is provided with a depending nut 22 (Fig. 2) engaging the constantly driven lead screw 23. The lead screw is driven from the main drive shaft 24 by gearing not herein shown. The moving 35 parts on the needle carriage are driven from a countershaft 25 carried thereon through a gear 26 meshing with a drive pinion 27, the latter splined on the drive shaft 24 and traveling with the carriage. The needle is 40 reciprocated by a link 28 having jointed connection to a pivoted arm 29, the latter in turn being oscillated by a link 30 connected to the crank disk 31 rotated by the needle drive shaft 32. The latter is driven by the 45 gear 33 meshing with the gear 26. The needle slides in a sleeve or cylinder 34 and is given a partial turn on its advance and retraction by devices not herein disclosed, but which include a pin upon the needle 50 engaging a partially spiraled slot in the sleeve. The movement of the needle is so timed that it undergoes one complete reciprocation as the carriage is advanced a space corresponding approximately to the spacing 55 between successive warp threads.

Acting in advance of the needle and herein in progressively advancing with the carriage, there is provided thread separating means for selecting and separating the foremost warp threads and positioning a thread 60 in the needle path for each thread drawing. Herein such thread separating device is in the form of a sleeve member 40 splined upon the driving shaft 12 the latter journaled in 65 the frame of the machine and driven from

the main drive shaft by means of the sprocket chain 42 (see Fig. 1) driven through the intermeshing gears 43 and 44, the latter fixed upon the main drive shaft. Referring to Figs. 7 to 9 inclusive, the sleeve member 40 has a corrugated tapered nose 45 which strokes the threads into parallelism, this being succeeded by a spirally grooved portion 46, the advancing lip of which picks up the foremost thread and conveys it into 70 the path of the needle. 75

The spirally grooved sleeve 46 can be angularly adjusted upon the sleeve member 40. For this purpose the sleeve 46 terminates in a flanged portion 47 having a recess 80 in which there is adapted to seat the pin 48 slidably mounted in the collar 49, the latter being fast to the sleeve 40 by means of the set screw 50 shown in Fig. 9. The opposite end of the pin 48 is threaded into a disk 51 85 which latter is normally held close against the face of the collar 49 by the stud 52. The latter has one end threaded into the collar but is provided with a head 53 sliding in a recess in the collar, a spring being interposed between the head and the bottom of the recess yieldingly to force the collar into the position shown. 90

The collar, however, may be drawn to the left (as viewed in Fig. 8) withdrawing the 95 pin 48 from the flange of the sleeve 47 whereupon the latter may be turned, thereby to adjust the lip of the screw or helix in different angular positions about the shaft. The flange 47 may be provided with a plurality of recesses distributed circumferentially about the same to permit of different positions of adjustment of the pin 376. 100

The collar 49 is circumferentially grooved as shown in Figs. 7 and 8 and rests by its 105 groove in the hook-shaped bracket 54 (Figs. 1 and 2) which latter is carried by a bent arm 55 fastened to an upright support 56 carried by the traveling needle carriage 21, so that the separating worm advances progressively across the machine always in fixed 110 relation to the needle, but being turned in suitably timed relation to present a thread for each thread drawing.

The free end of the thread, after being 115 drawn between the leaping members as hereinafter described, is drawn through a thread-guide eye 60 formed in the thread-guide 61 carried on the upright support 62 on the needle carriage and having an open slot 63 120 (Fig. 1) inclined obliquely down and away from the direction of travel of the carriage. When drawn, the thread end is stripped from the needle and down and out of the thread guide slot by the swinging stripper 125 arm 64 which sweeps down and across the path of the needle immediately following the retractile movement of the latter. A thread deflector 65 also assists in throwing the drawn-in thread farther away from the 130

needle carriage and the operating mechanism thereon.

The stripper arm 64 is slidably mounted in a sleeve 66 pivoted on the frame at 67 and is given a reciprocatory movement like that of a connecting rod through its connection to the crank disk 68. The latter is driven by the shaft 69 turned through the bevel gear 71, the latter carried upon the 10 needle drive shaft 32, the proportions of the gears being such that the stripper is caused to execute its stripper movement upon each retraction of the needle.

The threads when engaged by the needle 15 are drawn between suitably positioned lease members. These may be of any desired number and arranged for any required movement, but in the described machine they consist of a pair of flexible leasing 20 members, herein in the form of cords 75 and 76, and the separately movable, intermediate lease member, herein in the form of a cord 77. The cords are each arranged parallel with the travel of the needle lengthwise the machine, being held at their extremities preferably under tension. To this end each leasing cord is carried over pairs 25 of guide sheaves 78, one sheave being provided for each leasing cord at each end 30 of the machine and having journaled support on the frame members 2. At one end of the machine (left hand end as viewed in Fig. 1) each cord is fastened to a holder 79 secured to the upper end of a vertically 35 movable slide rod 80, the latter normally drawn down to produce tension in the cord by means of the coiled spring 81 interposed between a collar 82 on the rod and a guide box 83 through which the rod slides on the 40 machine frame. At its opposite end each leasing cord is secured by wrapping the same about the cleat 84 secured to the opposite frame member 2.

During the operation of the machine the 45 leasing cords 75, 76 and 77 are given vertical reciprocatory movement so as to place the cords 75 and 76 on the one hand and the single cord 77 on the other hand alternately above and below the plane of needle action. 50 For this purpose the cords when installed are initially drawn through guiding and holding devices carried by the needle carriage, herein in the form of tubular members, the tubular guide for the cord 75 being represented at 90, that for the cord 76 at 91, and that for the cord 77 at 92. These guiding and holding members are mounted upon vertically reciprocated supports actuated by the following mechanism. The 55 tubular guide 92 is fixedly secured to an arm 93^x (Figs. 1 and 2) fastened to the top of a vertically movable slide rod 93, the latter being guided for sliding in the upper and lower guide boxes 94 and 95 carried between 60 the two upright needle carriage supporting

arms 56 and 62. The slide rod 93 is normally held in its lowermost position by the coiled spring 96 interposed between a collar 97 at the bottom of the rod and the lower side of the guide box 95. It is adapted, 70 however, to be intermittently raised by suitably timed mechanism consisting of the lever arm 98 the forked end of which engages a roll 99 fastened to the side of the slide rod. The lever arm is pivoted at 100 75 on the needle carriage frame and is connected to the actuating arm 101, the latter carrying a cam roll 102 engaging with the edge cam 103 upon the countershaft 25. This mechanism provides for an up movement of the slide rod and tubular guide following one retractile movement of the needle and a downward movement of the slide rod and its tubular guide following the next retractile movement. 80

The tubular guides 90 and 91 for the lease cords 75 and 76 are similarly moved by slide rods 104 and 105 which rods are connected to move together by the cross head 106. The rods 104 and 105 have sliding movement in 90 the guide boxes 94 and 95 and are provided with restoring springs 96 similar to the restoring spring for the rod 93. The cross head 106 is vertically reciprocated by the forked end of the oscillatory lever 107 similar to the lever 98 and operated by a cam 108 on the shaft 25 but timed 180° apart from the timing of the cam 103 so that the tubular guides 90 and 91 move up as the tubular guide 92 moves down, and vice versa. 95

The result is that the two sets of lease members are caused to be alternately depressed and elevated at or about the path of the needle between successive thread drawings so that while positioned as shown in 100 Fig. 5, on one thread drawing, they are subsequently reversed in relation and positioned as shown in Fig. 6 on the next thread drawing. They are then returned to the position shown in Fig. 5 and so on, this resulting in the positioning of successively drawn threads on opposite sides of the lease cords. 105

In the described machine the thread as it is drawn between the lease members is also 110 drawn into engagement with suitable means which tend to retain it in approximately its drawn position and prevent the entanglement or displacement of the leased thread. In the described machine this is obtained by providing a series of closely arranged members, such as the resilient bristles 110 (shown only in Figs. 5 and 6) or the like, the lower ends of which are held fast on the supporting bar 111, the latter, however, being so positioned as to present the row of bristles transverse to the line of needle action. This results in causing the free ends of the threads to be drawn and laid in the bristles where they are held with sufficient certainty to 115 120 125 130

prevent the escape of the leased warp ends. The bristle holding support is omitted in Figs. 1 and 2 for the sake of clearness.

In order to move the leased threads back 5 from the line of action of the needle, means are provided for pressing back a drawn thread against the remainder of the already leased warp. This is conveniently accomplished herein by giving the tubular guides 10 an endwise thrust movement so that they tend to thrust or push the drawn-in threads back out of the line of action of the needle. Herein this endwise thrusting movement is imparted only to the tubular guides 90 and 15 91, the guide 92 being without such movement and this thread-displacing action taking place only at each alternate thread drawing. If desired, however, a similar movement could be imparted to the thread 20 guide 92.

For this purpose each of the tubular guides 90 and 91 is slidably mounted in its holding arm and devices are employed for reciprocatively moving the same therein 25 lengthwise the lease cord. The construction of the two guides in this respect is substantially the same, and that of the tubular guide 91 (shown in Figs. 3 and 4) only need be described. Referring to Figs. 3 and 4, 30 the guide 91 is slidably mounted in the arm 112, which latter is rigidly connected to the top of the slide rod 105 so that it is vertically reciprocated from the full line position shown in Fig. 3 to the dotted line 35 position therein shown. The tubular guide 91, however, at one end has the enlarged head 113 carrying the laterally projecting pin 114 working in a slotted end 115 of a rock lever 116. The latter is pivoted at 117 40 upon the lower end of the arm 112, but has a depending extension 118 provided with the lateral pin 119 working in a cam guide slot 120. The latter is formed in an adjacent part 121 projecting from the arm 56 and is 45 of such curvilinear form that as the arm 112 is vertically reciprocated the rock lever 116 and the tubular guide are reciprocatively moved between the full and dotted line positions shown in Fig. 3.

50 The result is that as the slide rods 104 and 105 are depressed, the tubular guides 90 and 91 are thrown quickly to the left (as viewed in Fig. 3), thrusting the drawn-in thread (designated at 10 in Fig. 3) to the left and 55 against the previously leased threads so that the tendency is constantly to thrust the leased threads out of the radius of the needle action.

The machine when operated imparts 60 movement to the needle carriage across the face of the warp, the needle being reciprocated and the leasing members alternately raised and depressed so that the entire warp is finally drawn and left in leased condition 65 with reference to the leasing cords.

If desired, compensating feed devices for the warp carriage may be employed similar to those described in the British patent aforesaid.

While I have herein shown and described 70 one form of the invention, it is to be understood that the same is not limited to the details herein shown, nor to the particular arrangement of operating parts, nor the mode of sustaining the warp with reference 75 to the operating elements of the machine, but that extensive modifications of the illustrated details may be made and wide departures therefrom followed without departing from the spirit of my invention. 80

Claims:

1. A machine for acting upon warp threads having a pair of flexible lease members, means to support a set of threads to be leased, means to engage successive threads of 85 one set and move them each in a direction lengthwise the thread, thereby to locate them in succession between the lease members, and means to deflect or bend the lease members to reverse the relation thereof to successive 90 threads.

2. A machine for acting upon warp threads having means for supporting an unleased warp, a plurality of flexible lease members having an initial position transverse the warp, and means for bending or deflecting said flexible lease members and for causing relative movement between the same and the threads of the warp taken in succession from one side thereof to the other 100 to place the threads in leased condition between the said members.

3. A machine for acting on warp threads having means for supporting an unleased warp, a pair of flexible lease members extending transverse the warp, and means for placing the warp in leased position relatively to the lease members including means acting progressively upon successive threads of the warp and traversing the warp and the lease members, and means also to bend or deflect the flexible lease members and cause relative movement between the same and the threads.

4. A machine for automatically placing 115 an unleased warp into leased formation embodying in combination with means to hold the unleased warp, a pair of flexible lease holding members, mechanism successively to separate and draw the warp thread ends, 120 said mechanism acting progressively thereon from one side of the warp to the other and devices to bend or deflect said lease holding members and put them successively into reversed relation to the threads after the 125 threads have been drawn by the said mechanism.

5. A warp leasing machine having means to hold an unleased warp, a pair of lease holding members, mechanism to successively 130

- separate and impart movement to warp threads in the direction of their length, means to cause relative movement between the warp threads and the said mechanism to 10 cause the latter to act progressively upon the threads from one side of the warp to the other, and means in fixed relation to the said mechanism but relatively movable to the warp to successively move the said lease members into reversed relation.
6. In a warp leasing machine, a thread-drawing device to draw the threads each in the direction of its length, a carrier therefor, a warp support, means to cause relative 15 traversing movement between the carrier and the warp support, a plurality of lease members, and means on the carrier for vibrating the lease members.
7. In a warp leasing machine, a thread-drawing device to draw the threads each in the direction of its length, a carrier therefor, a warp support, means to cause relative traversing movement between the carrier and the warp support, a plurality of flexible lease 20 members, and means on the carrier for vibrating the lease members.
8. In a warp leasing machine, a thread-drawing device to draw the threads each in the direction of its length, a carrier therefor, a warp support, means to cause relative 25 traversing movement between the carrier and the warp support, a plurality of flexible lease members, and means for vibrating the lease members.
9. In a warp leasing machine, a warp support, means to impart movement to individual threads of said warp, each in a direction lengthwise the thread, a carrier for said means, means to cause relative traversing 30 movement between the carrier and the warp support, a pair of flexible lease members, means on the carrier for vibrating the lease members comprising independent holding and guiding devices for the lease members, 35 and means for reversely reciprocating the same to move them across the path of the thread-placing device following each threading movement thereof.
10. In a warp leasing machine, a thread-drawing needle, a carrier therefor, a warp support, means to cause relative traversing movement between the carrier and the warp support, a pair of flexible lease members, means on the carrier for vibrating the lease 40 members comprising independent holding and guiding devices for the lease members, and means for reversely reciprocating the same to move them across the path of the thread-drawing needle following a threading movement thereof.
11. In a machine for acting upon warp threads, the combination with means for supporting a warp in unleased condition of a device for imparting movement to successive 45 threads of said warp each in a direction lengthwise the thread, flexible leasing members coöperating therewith for placing a warp in a leased condition and means to bend or deflect said leasing members.
12. In a machine for leasing warps, the 50 combination with means for holding the warp, flexible means adapted to hold the lease extending initially transverse the warp, means to place the warp threads with relation to the lease-holding means, and means 55 adapted to bend or deflect the said lease holding means reciprocally from one side to the other of the plane of the warp.
13. In a machine for leasing warps, the 55 combination with warp holding means, of 60 flexible lease holding members, means for drawing the warp threads in succession from one side of the lease holding members to the opposite side thereof, and means to bend or deflect the said holding members after each 65 warp thread is placed between them to reciprocate alternately from one side to the other of the drawn threads.
14. In a warp leasing apparatus, a pair of parallel flexible leasing members, mechanism for reversely and intermittently vibrating the same, means for causing progressive traversing movement between said members and said mechanism, thread placing means and means to move the leased threads out of 70 the path of movement of the thread placing means.
15. In a warp leasing apparatus, a pair of parallel flexible leasing members, mechanism for reversely and intermittently 75 vibrating the same, a carriage sustaining said mechanism, means for causing said carriage to progressively travel lengthwise the said members and a coöperating thread drawing device for drawing the thread ends between 80 the leasing members.
16. A warp leasing machine having means for holding a warp, a thread-placing device, a carriage therefor, carriage traversing mechanism, devices for giving the thread-placing device intermittent reciprocatory movement to engage and position successive threads, a plurality of flexible lease members extending transversely the warp and between the same and the thread placing device and between which members the threads are placed, the carriage being traversed past the machine and the lease members, and means for shifting the relation of the lease members between successive actions of the 85 thread-placing device.
17. A warp leasing machine having means for holding a warp, a thread placing device, a carriage therefor, a carriage traversing means, mechanism for giving the thread-placing device an intermittent, reciprocatory movement to engage successive threads, a plurality of supports held at their ends under maintained tension and between 90 which the threads are successively placed 120
- 60 threads of said warp each in a direction 125

by said thread-placing device, said carriage being moved across the warp lengthwise the cords, and means for reversing the relation of the said cords between successive actions 5 of the thread-placing device by bending or deflecting said supports between their held ends.

18. A warp leasing machine having means for holding a warp, a thread-drawing device for drawing the thread ends, a carriage therefor, carriage traversing means, mechanism for giving the thread-drawing device an intermittent reciprocatory movement to engage successive threads, a plurality of cords held at their ends under maintained tension and between which the thread ends are successively placed by said thread-drawing device, means carried by the carriage for reversing the relation of the said 15 cords between successive actions of the thread-drawing device.

19. A warp leasing machine having means for holding a warp, a thread-drawing device for drawing warp thread ends, a carriage therefor, carriage traversing means, mechanism for giving the thread placing device an intermittent reciprocatory movement to engage successive threads, a plurality of cords held at their ends under maintained tension and between which the thread ends are successively placed by said thread-placing device, and means comprising intermittently moving holding members through which the cords are adapted to pass freely 30 and which sustain the cord for reversing the relation of the cords between successive actions 35 of the thread-placing device.

20. A warp leasing machine having means for holding a warp, a thread-placing device, 40 a carriage therefor, carriage traversing means, mechanism for giving the thread-placing device an intermittent reciprocatory movement to engage successive threads, a plurality of cords held at their ends under maintained tension and between which the threads are successively placed by said thread-placing device, separate holding members on said carriage for said cords through which the latter freely pass, means 45 for reversely and intermittently vibrating said holding members to reverse their relation to the path of the thread-placing device, and means also to give said members a longitudinal movement to press the leased 50 thread out of the line of action of the thread-placing device.

21. A warp leasing machine having thread-placing means, flexible leasing members, holding means through which the leasing 60 members freely pass, means to reversely and intermittently vibrate the leasing members, and means to give a longitudinal movement to the holding means to force back the leased thread.

22. A leasing machine having flexible

leasing members, holding members through which the leasing members freely pass, means for reversely and intermittently vibrating the holding members comprising a reciprocatively movable support for each, a lever pivoted thereon and having a portion guided in a stationary cam slot to give it a swinging movement, the opposite end being connected to the holding member to longitudinally reciprocate the same. 75

23. In a leasing machine, means to support an unleased warp, a coacting thread drawing device for drawing thread ends, means for supporting in longitudinally extended relation a plurality of flexible leasing 80 elements, means engaging the same and relatively movable to progressively vibrate the elements for alternately and intermittently reversing their relation.

24. A machine for acting upon warp 85 threads having a support for an unleased warp, a pair of flexible lease members extending initially transverse the extent of the warp, means to engage successive warp threads to locate them in succession between the lease members, and means to bend or deflect the lease members to reverse the relation thereof to successive threads.

25. A machine for acting upon warp threads having a pair of flexible lease-members, means to support a set of threads to be leased, means to draw successive thread ends of said set in succession between the lease members, and means to reverse the relation of said lease-members with respect to successive threads by bending or deflecting the same. 95

26. A machine for acting upon warp threads having a pair of flexible lease-members, means to support a set of threads to be 100 leased, a drawing needle to draw threads in succession from said set between the lease-members and means to move the lease-members to reverse the relation thereof to successive threads. 110

27. In a machine for acting upon warp threads, the combination with means for supporting a warp in unleased condition, of a thread drawing device for drawing warp thread ends, flexible leasing means coöperating therewith for placing a warp in a leased condition and means for spreading said flexible leasing means to receive the drawn threads. 115

28. In a warp leasing apparatus, a pair 120 of parallel flexible leasing members, mechanism for reversely and intermittently vibrating the same, means for causing progressive traversing movement between said members and said mechanism, and coöperating thread drawing means for drawing successive thread ends between said leasing members. 125

29. A warp leasing machine having thread placing means, leasing members, holding means through which the leasing members 130

freely pass, means reversely and intermittently to vibrate the leasing members, and means to give a longitudinal movement to the holding means to force back the leased 5 thread.

30. A machine for acting upon warp threads having a pair of flexible lease-members, means to support a set of threads to be leased, means to engage successive threads 10 of said set to move them each in the direction of its length, thereby to locate them in succession between the lease members, and means to move the lease members to reverse the relation thereof to successive threads, said 15 means including slides carrying tubes for said lease-members and levers having arms constantly engaging said slides to impart movement thereto.

31. A machine for acting upon warp 20 threads having a pair of flexible lease-members, means to support a set of threads to be leased, means to engage successive threads of said set to move them longitudinally, thereby to locate them in succession between the 25 lease-members, and means to move the lease-members to reverse the relation thereof to successive threads, said means being located wholly below said lease-members.

32. A machine for acting upon warp 30 threads having a pair of flexible lease-members, means to support a set of threads to be leased, separating means extending transversely of the plane of said set of threads, means to engage successive threads of said 35 set to move them each in the direction of its length, thereby to locate them in succession between the lease-members, and means to move the lease-members to reverse the relation thereof to successive threads.

40 33. A machine for acting upon warp

threads having a pair of flexible lease-members, a thread drawing member and a thread separating member positioned at substantially right angles to each other, means to support a set of threads to be leased in proximity to said members, and means to move the lease-members to reverse the relation thereof to successive threads. 45

34. A machine for acting upon warp threads having a pair of flexible lease-members, a thread separating device, a set of threads supported in proximity to said separating device and extending in a downward plane below said separating device, means to engage successive threads of said set to move 50 them each in the direction of its length, thereby to locate them in succession between the lease-members, and means to move the lease-members to reverse the relation thereof to successive threads. 55

35. A machine for acting upon warp threads having a pair of flexible lease-members, a separating device for the threads of a warp, a warp having its threads supported in angular formation, said separating device 60 being at the apex of the angle thereof, means to engage successive threads of said warp to move them longitudinally thereby to locate them in succession between the lease-members, and means to move the lease-members to reverse the relation thereof to successive threads. 65

In testimony whereof, I have signed my name to this specification in the presence of two subscribing witnesses.

CHARLES D. LANNING.
